UNITED STATES PATENT OFFICE

149,394

DESIGN FOR A BOTTLE OR ARTICLE OF
SIMILAR NATURE

John S. Allen, Montgomery, Ala.

Application March 27, 1946, Serial No. 128,003

Term of patent 7 years

(Cl. D58—8)

To all whom it may concern:

Be it known that I, John S. Allen, a citizen of the United States of America, residing at Montgomery, in the county of Montgomery, State of Alabama, have invented a new, original, and ornamental Design for a Bottle or Article of Similar Nature, of which the following is a specification, reference being had to the accompanying drawing, forming part thereof.

Fig. 1 is a front elevation of a bottle, showing my new design, and

Fig. 2 is a bottom view thereof.

I claim:

The ornamental design for a bottle or article of similar nature, as shown.

JOHN S. ALLEN.
